CLAIM

I claim the ornamental design for a highball glass and straw,
as shown and described.

DESCRIPTION

FIG. 1 is a right side elevational view showing my new
design;

FIG. 2 is a front elevational view thereof;

FIG. 3 is a top plan view thereof;

FIG. 4 is a left side elevational view thereof;

FIG. 5 is a rear elevational view thereof; and,

FIG. 6 is a bottom plan view thereof.
